Ida E. Tebo.
INVENTOR

UNITED STATES PATENT OFFICE.

IDA E. TEBO, OF BROOKLYN, NEW YORK.

DESIGN FOR A SWEATER.

53,646.

Specification for Design.

Patented July 22, 1919.

Application filed February 4, 1919. Serial No. 275,081. Term of patent 3½ years.

To all whom it may concern:

Be it known that I, IDA E. TEBO, a citizen of the United States, residing at Brooklyn, county of Kings, State of New York, have invented a new, original, and ornamental Design for Sweaters, of which the following is a specification, reference being had to the accompanying drawing, forming part thereof.

The figure is a perspective view of a sweater, embodying my new design.

I claim:

The ornamental design for a sweater, as shown.

IDA E. TEBO.
